(57) **CLAIM**

The ornamental design for a sun shelter, as shown and described.

DESCRIPTION

FIG. 1 is a perspective view of our sun shelter;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dot broken lines immediately adjacent the shaded areas represent the bounds of the claim. All other broken lines, including the mesh/screened areas, represent unclaimed portions of the sun shelter. None of the broken lines form a part of the claimed design.
